UNITED STATES PATENT OFFICE.

JOHN P. BRYANT, OF CHICAGO, ILLINOIS.

EYELET TACK.

Application filed February 23, 1922. Serial No. 538,809.

To all whom it may concern:

Be it known that I, JOHN P. BRYANT, a citizen of the United States, and a resident of the city of Chicago, county of Cook, and State of Illinois, have invented certain new and useful Improvements in Eyelet Tacks, of which the following is a specification.

This invention relates to Eyelet tacks and has for its object the provision of a tack of this character, which may be driven to position without injurious distortion thereof, and which is simple in construction, efficient in operation and economical of manufacture.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front elevation of the invention in operative position;

Fig. 2 is an elevation of the blank from which the tack is formed;

Fig. 3 is an elevation of the completed tack; and

Fig. 4 is a side view partly in section of the invention applied to a window shade.

Fig. 5 is a sectional view taken on the line 5—5, Fig. 3.

The eyelet tack comprises a body portion 10, which may be stamped from any suitable material, and has a laterally extending wing 11, and a pointed end 12. The body member 10 is concaved, and the wing portion 11 is bent over said body portion 10, as shown in Fig. 5, the edge 13 of the wing portion 11 being preferably lapped beneath the edge 14 of the body portion 10. The concaved body 10 of the tack preferably tapers to the point 12 which is preferably flattened and sharpened.

As will be noticed due to the concaved body portion of the tack and the general construction of same, such tack may be driven to any desired depth without fear of injuriously distorting the eyelet formed thereon by the wing 11.

Though the tack is adapted for use in any

desirable situation such tack is illustrated as applied to a window shade 15, which is provided with the usual stiffening member or stick 16. As shown in Fig. 4, the sharp point 12 of the tack is driven through the stiffening member 16 of the window shade and the inner end thereof clinched as shown at 17 against the stiffening member. The body member adjacent the eyelet formed on the tack member may be downwardly bent if desired, as shown in the present adaptation of the invention. A flexible member 18, or other suitable member may be secured in said eyelet in any suitable manner, said flexible member in this instance having a knot 19 at one end to prevent same being drawn through said eyelet.

An important feature of the present invention is to provide an eyelet tack which may be driven to operative position, without distortion thereof and bent at a convenient angle, if desired, to provide an eyelet in which may be fastened any suitable securing member.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claim.

Having described my invention, what I claim as new and desire to secure by Letters Patent is:

In combination with a curtain shade stick, a tack having a concave body portion and a wing portion bent thereover to form an eyelet, said tack driven into said stick, and bent so that the eyelet lies thereagainst; and a flexible member secured in said eyelet.

In testimony whereof I have signed my name to this specification in the presence of two subscribing witnesses.

JOHN P. BRYANT.
